CENTRIFUGAL PUMP

John Mann, Seneca Falls, N. Y., assignor to
Goulds Pumps, Inc., Seneca Falls, N. Y., a corporation of New York

Original application July 9, 1937, Serial No.
152,801. Divided and this application October
10, 1938, Serial No. 234,112

7 Claims. (Cl. 103—111)

My invention relates to new and useful improvements in centrifugal pumps, and is a division of my application, Serial No. 152,801, filed July 9, 1937.

5 An object of my invention is to provide an efficient and simple means for sealing the impeller drive shaft to protect the shaft from the corrosive and abrasive action of the liquid being pumped.

10 Another object of my invention is to provide a seal to prevent access to the impeller drive shaft of the liquid being pumped without the use of packing between the sealing surfaces.

15 More specifically, my invention contemplates a cap having an annular surface adapted to engage the hub of the impeller and be drawn up tightly thereagainst for the purpose of not only retaining the impeller on its shaft, but also for the purpose of forming a seal without 20 the use of packing between the mating surfaces adapted to withstand high pressures.

Other objects and advantages of my invention will be apparent from the following description when taken in connection with the accompanying drawing, in which:

25 Fig. 1 is a sectional view showing the pump casing, the impeller, the stuffing box assembly, and other parts of the pump to which my invention is applied.

30 Fig. 2 is an enlarged sectional view of a portion of Fig. 1 and showing the details of my invention.

35 Fig. 3 is a sectional view somewhat similar to that of Fig. 2 showing a pump impeller, in which the hub of the impeller is solid instead of perforated as shown in Figs. 1 and 2.

40 While the novel means of my invention may be embodied in any type of centrifugal pump, I have shown the invention as applied to what is known in the art as a "close coupled" pump. The primary differences between a close coupled pump and other types of centrifugal pumps are that, in a close coupled pump, the motor and pump casings are, by what is known as an adapter, rigidly secured closely together and the 45 drive shaft is common to both the motor and the pump.

The assembly in which the novel means of my invention is incorporated comprises a motor 41, only the end of which is shown, adapter 42 and a pump casing generally indicated by the numeral 43. The adapter is provided with hand holes to enable access to the stuffing box unit. The adapter, as shown in Fig. 2, is rigidly bolted, as indicated at 44, to the motor casing and the pump casing is, in turn, rigidly bolted, as indicated at 45, to the adapter. Any suitable means may be provided for rigidly securing the pump and its motor to the floor, no special foundation being required with this type of pump. If

desired, the pump unit may be secured in a vertical position, as the unit is particularly adapted to operate in any position.

The pump casing comprises a casing proper 17 and a cover plate 18 which may be bolted thereto as indicated at 19. The shaft 21, which is common to both the motor and the pump, has a suitable bearing 22 at the pump end of the motor casing and another bearing (not shown) at the other end of the motor casing. 10 That portion of the shaft 21 which extends beyond the motor casing 11 is overhung and extends through the adapter and into the pump casing 13. To the end of the shaft 21, by means of a key 23, is secured, against rotation, with 15 respect to the shaft, the hub 24 of an impeller 26. The impeller is usually made of bronze and is held in position on the shaft by means which will be later described.

20 The impeller comprises a web 27, a plurality of vanes 28 preferably cast integrally with the web, and a shroud 29 which may be riveted or otherwise secured to the vanes. The shroud as it approaches the impeller axis curves outwardly, as indicated at 31, to form a smooth entrance for 25 fluid into the impeller, commonly called the eye of the impeller. At its central portion the shroud is flanged outward, as indicated at 32, to provide a fluid entrance or suction opening into the impeller. The suction pipe 33 is threaded, as indicated at 34, in an opening in the cover plate 18 and is in axial alignment with the flange 32 of the impeller so that fluid being drawn through the suction pipe, or flowing thereto by gravity, will smoothly enter the eye of the pump impeller. 35 The pump casing has a volute 36 and wearing rings 37, and these and other details of the pump are preferably formed as described in the above-mentioned parent application.

40 The pump is further provided with a stuffing box 38 and a packing gland 39, which is adapted, when drawn into the stuffing box, to tightly compress suitable packing 41. The stuffing box is further provided with a liquid seal, generally indicated by the numeral 42, as is customary in the art to which this invention applies. While any suitable type of stuffing box may be employed, preferably the stuffing box is threaded into a bore in the casing as shown at 43. A bronze casing wearing ring 44 fixed in a bore of 45 the stuffing box, and with respect to which the hub 24 of the impeller is rotatable, may be provided.

46 In the past, various methods have been employed for preventing the liquid being pumped 50 from gaining access to the drive shaft. If the liquid being pumped gains access to the shaft, corrosion quickly results, and in cases where the liquid contains solids, such as sand, abrasion of 55 the shaft occurs. In most of the methods of 60

preventing the liquid from gaining access to the shaft, packing is employed. While packing suited to various conditions and of materials designed particularly to resist the action of the various liquids which may be pumped, are available, all types of packing are subject to deterioration, and are a source of trouble. The pump must quite often be dismantled and the packing replaced when it has become worn.

10 In the pump of my invention I have provided novel means for retaining the impeller on the shaft, and at the same time preventing access of the liquid being pumped to the shaft. This construction is more clearly shown in Fig. 2. A shaft sleeve 51 is mounted on the shaft 21 and confined against movement along the shaft in a direction to the right, as viewed in Fig. 1, by butting it against a shoulder 52 on the shaft. The other end of the shaft sleeve, which, as is the usual practice, is made of bronze, has a tapered countersuction portion, as indicated at 53, so as to provide an annular bearing surface 54 of restricted area which is ground and finished.

25 A threaded bore 56 is provided in the end of the shaft along the axis thereof into which is threaded a socket head tap bolt 57. The bolt 57 has a suitable opening 58 for the reception of a wrench. A sealing member or washer 59 is confined between the head of the bolt and the hub 24 of the impeller. The washer is provided with an annular sealing surface 61 of restricted area, which is ground and finished. The mating face 62 of the hub with the sealing surface 61, and the mating face 63 with the sealing surface 35 54 formed on the sleeve 51, are preferably ground and finished. It will be particularly noted that the annular sealing surface 61 is the only portion of the washer which engages the hub of the impeller. The washer does not engage the shaft at 40 any point. It will further be noted that when pressure is applied on the washer, the hub of the impeller is pressed tightly against the sealing surface 54 formed on the sleeve 51, and that the sleeve 51 is pressed tightly into engagement with 45 the shoulder 52 on the shaft 21.

In practice, particularly in small pumps, since access to the bolt must be had through the eye or suction opening of the impeller, the size of the bolt is within rather small limits fixed by 50 the diameter of the impeller suction opening. Moreover, the diameter of the shaft in small pumps does not permit the use of a large diameter bolt, and further, as is apparent upon consideration of Fig. 1, a bolt with a large diameter head 55 restricts the free flow of water through the impeller. With these considerations limiting the size of the bolt in mind, the bolt head and the diameter of the bolt at the root of the thread (the dimension N) are made as large as possible. 60 Then to obtain the maximum sealing pressure between the annular sealing surface 61 of the washer 59 and the hub and between the annular sealing surface 54 of the sleeve 51 and the hub, the areas of the sealing surfaces 61 and 54 are made equal to the area of the bolt at the root 65 of the thread.

When the bolt is tightened up by a man, in the ordinary manner, so that the bolt is loaded within the elastic limit of the material of the bolt, the pressure applied on the bolt is transmitted to the sealing surfaces 61 and 54. This places the maximum pressure possible at the seal points without destroying the surface contacts between the sealing surfaces and the hub. 70 It will be appreciated that if the areas 61 and

54 are made larger than the area of the bolt at the root of the thread (the dimension N), the pressure at the sealing surfaces will not be the maximum amount possible. If the areas 61 and 54 are made smaller than the bolt area at the root of the thread, then the pressure applied on the sealing surfaces may be sufficiently great to destroy the surface contacts at the sealing surfaces. When the sealing surfaces are loaded just within their elastic limit, the whole area of the machine surfaces at the sealing points will be in contact because any slight unevenness of the surfaces will be crushed out for the reason that the areas of these uneven surfaces will be less than the area of the bolt at the root of the 10 thread and the sealing surfaces 61 and 54 will imbed themselves slightly into the hub of the impeller. The seal thus provided effectively prevents the liquid being pumped from gaining access to the shaft and is capable of withstanding 15 a pressure of approximately three hundred pounds per square inch, a pressure far above the pressure which the seals may be called upon to withstand. The shaft seal described eliminates the use of troublesome packing. A copper sealing ring 66 is interposed between the head of the tap bolt 57 and the washer 59 which effectively prevents leakage along the threads of the bolt. If desired, the bolt and washer may be made integral, although I do not consider this 20 construction as desirable, because it is preferable that, in drawing up the tap bolt 57, rotation of the tap bolt with respect to the washer 59 be permitted. Also if desired, instead of using a tap bolt threaded into a threaded bore in the shaft, 25 as shown herein, the end of the shaft may project slightly beyond the hub of the impeller. The projecting end may then be threaded to receive a nut and there may be interposed between the nut and the hub of the impeller a washer having 30 a sealing surface engaging the hub of the impeller. 35

The hub of the impeller of the pump thus far described is provided with openings 67 spaced around the hub so that the pressure on both sides of the hub will be the same and the impeller will, therefore, be substantially hydraulically balanced since the pressures in the discharge chamber on opposite sides of the impeller are the same. In Fig. 3 I have shown how the shaft seal above described may be applied to an impeller in which the apertures through the hub of the impeller are omitted and the impeller is not, therefore, hydraulically balanced. The construction is the same as that described above, differing therefrom only in the omission of the apertures and in the omission of an impeller wearing ring corresponding to the wearing ring 40 of the structure shown in Fig. 1.

It will be appreciated that I have provided a novel construction for preventing access to the shaft of the liquid being pumped, and that while I have shown my invention as applied to a close coupled centrifugal pump, the invention has other applications, particularly to other types of centrifugal pumps. It will further be appreciated that various modifications may be made in the form and relation of parts of the structure shown and described without departing from the spirit of my invention as set forth in the appended claims.

I claim:

1. A pump of the character described wherein an overhung shaft extends into a casing comprising, in combination, an impeller having a 75

- hub mounted in said casing on the end of said shaft, said hub having a plurality of apertures to permit the free flow of liquid from the back of the impeller to equalize the pressure on opposite sides of the impeller, a sleeve mounted on said shaft and confined against movement along the shaft, a bolt threaded into the end of the shaft concentric with the axis thereof, said bolt having a head, a cap confined between the head 10 of said bolt and the end of the shaft, said cap being out of contact with the end of the shaft and engaging the hub of the impeller, said bolt having a cross sectional area at the root of the thread equal to the area of contact between the cap and the hub of the impeller and equal 15 to the area of contact between the hub of the impeller and the end of said sleeve whereby when the bolt is drawn up tightly, the impeller is secured to said shaft and the pressure applied 20 seals the surfaces between the cap and the hub and between the hub and the sleeve to prevent access to the shaft of the liquid being pumped.
2. A pump of the character described wherein an overhung shaft extends into a casing comprising, in combination, an impeller having a hub mounted in said casing on the end of said shaft, a bolt threaded into the end of the shaft concentric with the axis thereof, said bolt having a head, a cap confined between the head of 25 said bolt and the end of the shaft, said cap being out of contact with the end of the shaft and engaging the hub of the impeller, said bolt having a cross sectional area at the root of the thread substantially equal to the area of contact 30 between the cap and the hub of the impeller whereby when the bolt is drawn up tightly the pressure applied seals the surfaces between the cap and the hub to prevent access to the shaft of the liquid being pumped.
3. In a machine of the class described, a shaft, an impeller having a hub mounted on said shaft, said hub having a ground and finished surface, means for preventing leakage of fluid along the shaft comprising a cap having an annular ground and finished contact surface engaging the ground 35 and finished surface of the hub and encircling the end of the shaft, and means for applying pressure on said cap, said pressure being sufficient to crush out any unevenness between the mating surfaces of the cap and the hub whereby a liquid seal is formed to prevent access to the shaft of the liquid being pumped.
4. In a pump of the class described, in combination a pump shaft, an impeller having a hub mounted on said shaft, means for preventing leakage of fluid along the shaft comprising a cap having an annular contact surface of limited 40 area engaging the hub of the impeller encircling the end of the shaft, said cap being out of contact with the end of the shaft, and means comprising a bolt threaded into the end of the shaft for applying pressure on said cap, said bolt having a cross-sectional area at the root of the thread substantially equal to the area of contact 45 between the cap and the hub of the impeller, the pressure applied between the mating surfaces of said cap and hub being sufficient to crush out any unevenness between the mating surfaces of the cap and the hub so that a liquid seal is formed to prevent access to the shaft of the liquid being pumped without the use of packing.
5. A pump of the character described wherein an overhung shaft extends into a casing comprising, in combination, an impeller having a hub mounted in said casing on the end of said shaft, said hub having ground and finished surfaces on both ends thereof, a sleeve mounted on said shaft, means for preventing the sleeve from moving along the shaft, means for retaining the impeller on said shaft with one of the ground and finished surfaces of the hub in engagement with the end of the sleeve comprising a cap having 50 a ground and finished surface of limited area adapted to engage the other ground and finished surface of the hub, said cap being out of contact with the end of the shaft, and means for applying pressure on said cap comprising a threaded member between the cap and the end of the shaft, said cap when pressure is applied applying pressure between the ground and finished surfaces of said cap and hub and between the meeting surfaces of said hub and sleeve.
6. A pump of the character described wherein an overhung shaft extends into a casing comprising, in combination, an impeller having a hub mounted in said casing on the end of said shaft, said hub having a plurality of apertures to permit the free flow of liquid from the back of the impeller to equalize the pressure on opposite sides of the impeller, a sleeve mounted on said shaft and confined against movement along the shaft, said sleeve engaging one side of the hub, a cap having a small area of contact with the other side of the hub and being out of contact with the end of the shaft, said cap and hub having ground and finished cooperating engaging surfaces, and means including a threaded member 55 between the end of the shaft and the cap for applying pressure between said ground and finished surfaces and between the hub and the end of the sleeve, said threaded member having a cross sectional area at the root of the thread substantially equal to the area of contact between the cap and the hub of the impeller and substantially equal to the area of contact between the hub of the impeller and the end of said sleeve whereby when pressure is applied the impeller is secured to said shaft and the pressure applied seals the surfaces between the cap and the hub to prevent access to the shaft of the liquid being pumped.
7. In a pump of the class described, in combination, a pump shaft, an impeller having a hub mounted on said shaft, said hub having a ground and finished surface, means for preventing leakage of fluid along the shaft comprising a cap having an annular ground and finished contact surface of limited area engaging the ground and finished surface of the hub of the impeller, said cap being out of contact with the end of the shaft, and means comprising a threaded member between the end of the shaft and the cap for applying pressure on said cap, said threaded member having a cross sectional area at the root of the thread substantially equal to the area of contact between the cap and the hub of the impeller, the pressure applied between the mating surfaces of said cap and hub being sufficient to crush out any unevenness between the mating surfaces of the cap and the hub so that a liquid seal is formed to prevent access to the shaft of the liquid being pumped without the use of packing.

JOHN MANN.
